BALL RUNWAY TOY

Alec Klein, Salt Lake City, Utah
(9896 Sunflower Lane, Sandy, Utah)
Filed July 24, 1961, Ser. No. 126,133
2 Claims. (Cl. 273—109)

The present invention relates to ball runways toys and, more particularly, to a new and improved ball runway toy which may be fabricated conveniently from very thin sheet metal, and this in a manner and by means which will add rigidity to the over-all structure.

In the past many types of ball runway toys have been devised. This type of toy provides a great deal of amusement for children and, indeed, adults who use the same. The toys are conventionally actuated by an arm or wrist movement of the handle extending from the raceway or runway of the toy, this in such a manner that the ball disposed in the runway will travel rapidly in an arcuate motion about the runway in accordance with the motion of the toy's handle.

Prior toys of this type have been very expensive to manufacture since conventional materials used in fabricating the toy are generally either heat formed, or composed of a number of parts, or are otherwise expensive to construct. Further, if the runway is made of very light metal, as suggested herein, then prior structures will conventionally employ a very heavy handle which is welded or otherwise secured to the runway member as a separate part.

An object of the present invention, therefore, is to provide a new and improved ball runway toy which may be fabricated from a single elongate member in combination with a suitable handle stiffener or brace.

A further option of the invention is to provide a ball runway toy which will be extremely versatile in operation and yet present a low manufacturing cost.

The features of the present invention which are believed to be novel are set forth with particularity in the appended claims. The present invention, both as to its organization and manner of operation, together with further objects and advantages thereof, may best be understood by reference to the following description, taken in connection with the accompanying drawings in which:

FIGURE 1 is an exploded, perspective view of the channel member and handle brace employed in the construction of the present invention.

FIGURE 2 is a side elevation of the completed, ball runway toy, with the channel member thereof partly broken away to show the cooperation of the inner end of the handle brace with the arcuate portion of the channel member.

FIGURE 3 is an enlarged view taken along the line 3—3 in FIGURE 2 and illustrates the manner in which the end of the channel member is deformed within and secured to a medial area of the channel member so as to form the arcuate ball runway.

FIGURE 4 is a section taken along the line 4—4 in FIGURE 3.

FIGURE 5 is an enlarged view similar to FIGURE 3 and shows an alternate construction of deforming and providing relief for the end of the channel member so as to aid its securement to a medial area of the channel member.

FIGURE 6 is a perspective view of the toy in operation.

In FIGURE 1 the channel member 10 is shown; it may be either preformed or channel-configured in fabrication from strip, sheet-stock of very thin (20 to 30 gauge) sheet metal. Handle brace 11 is preferably made of wood but also may be fabricated from other materials such as plastic, rubber, or even metal, though the latter

2

would generally not be the case. Where the handle brace 11 is made of wood, plastic or rubber, then the same may be secured within the channel member in part by having the corners 12 and 13 crimped inwardly, as shown by dotted configurations 14 and 15, so as to retain the handle brace 11 in its chosen position within channel member 10 as shown in FIGURE 2. It will be seen that this securement is effective so far as the rear end 16 of handle brace 11 is concerned. The front end 17 of handle brace 11 is preferably of concave configuration so as to be adapted to nest underneath and press against the arcuate, preferably cylindrical portion 18 of member 10. FIGURE 2 illustrates that the end 17 of handle brace 11 is directly against arcuate portion 18 so as to lend rigidity to arcuate portion 18 in addition to securing the mounting of handle brace 11 within channel member 10. The result is a very rigid construction, i.e. a very rigidly constructed handle portion 19, composed of the upper portion 20 of channel member 10 with handle brace 11, and a rigid bracing of the arcuate portion 18 by virtue of the contact of arcuate end 17 of handle brace 11 with arcuate portion 18.

It will be understood, however, that various end configurations for end 17 may be employed. Thus, an angular configuration or even a squared-off configuration might reasonably be employed, this so long as at least a portion of the end 17 contacts the under-surface of arcuate member 18 as shown in FIGURE 2.

It is to be observed with reference to FIGURE 2 that slight deformations 21 persist in the vertical channel member 10 once the same has been formed to include the arcuate portion 18. Prior constructions have quite generally not taken this fact into consideration and, indeed, have avoided such a consequence by heat forming the toy or by otherwise employing expensive, curved channel materials. The present invention allows for such deformities 21 and utilizes the same to accomplish an initial placement of end 22 into medial region 23 of member 10. Where the arcuate configuration of channel member 10 is accomplished through a roller means employing a pair of closely spaced annular grooves to accommodate the channel sides, it has been found in practice that these deformities 21, allowed to take place through a slight enlargement widthwise of the annular grooves, will occur at regular intervals. Thus, the deformities 21 will "match up" when fabrication is completed and the end 22 appropriately positioned to be affixed to and within the medial region 23 of member 10. These inter-cooperating deformities 21 aid in the initial placement of end 22 so that spot welding as at 24 in FIGURES 3 and 4 may be accomplished.

Also aiding this final securement of the toy is the fact that the end 22 is provided with a slit 25 which is either narrow as shown in FIGURE 3, or is relatively wide as at 25' in FIGURE 5. If the end 22 is provided with a narrow slit as at 25 in FIGURE 3, then adjacent portions 27 and 27' will overlap so as to enable the end 22 to be positioned within the remainder of channel member 10 at medial region 23.

Where the slit is wide as at 25' in FIGURE 5, then no overlapping will take place; however, the adjacent parts of member 10 which are contiguous with the slit 25' may be compressed inwardly and yet, by virtue of the inherent resiliency of the material, will press outwardly so as to contact in a tight friction engagement the sides of channel member 10 at medial region 23.

Again, the deformities 21 which occur by virtue of the bending of arcuate portion 18 (see FIGURE 2, not shown for convenience of illustration in FIGURES 3 and 5) will aid in accomplishing initial positioning of arcuate portion 18 to accommodate the spot welds at 24 in FIGURES 3 and 5.

FIGURE 4 is merely a section of that portion of the structure shown in FIGURE 3, and illustrates the overlapping end portions 27' and 27 at the slit area 25.

FIGURE 6 illustrates the toy in operation, with the ball 28 thereof progressing along the runway formed by channel member 10 at arcuate portion 18 thereof. The toy provides a great deal of amusement for children who, by a preferable wrist action, can actuate the toy in a transverse vibrating motion so as to cause the ball 28 to speed around its runway rapidly. This feat can be accomplished not only when the toy is being held to the front and in a vertical plane, but also when the toy is held in a horizontal plane either at the front, at the side, or above the user.

While particular embodiments of the present invention have been shown and described, it will be obvious to those skilled in the art that changes and modifications may be made without departing from this invention in its broader aspects, and, therefore, the aim in the appended claims is to cover all such changes and modifications as fall within the true spirit and scope of this invention.

I claim:

1. A ball runway toy including in combination, a channel member having an elongate handle portion and an arcuate, doubled-back runway portion, the end of said arcuate, doubled-back runway portion being affixed to a medial region of said channel member in proximity with the junction of said arcuate, doubled-back portion and said elongate handle portion, and a handle brace fixedly disposed within said elongate handle portion and having an inner end supportingly abutting said arcuate, doubled-back portion.

2. Structure according to claim 1 wherein said inner abutting end of said handle brace is of concave configuration lapped with said arcuate, doubled-back portion.
